UNITED STATES PATENT OFFICE.

HERMAN H. SUNVOLD, OF SACRED HEART, MINNESOTA.

REAR-AXLE TRUSS.

1,108,812.

Specification of Letters Patent. Patented Aug. 25, 1914.

Application filed February 26, 1914. Serial No. 821,267.

To all whom it may concern:

- Be it known that I, HERMAN H. SUNVOLD, a citizen of the United States, residing at Sacred Heart, in the county of Renville and 5 State of Minnesota, have invented certain new and useful Improvements in Rear-Axle Trusses, of which the following is a specification, reference being had therein to the accompanying drawing.
- 10 This invention relates to a rear axle truss for automobiles, and the principal object of the same is the provision of a simple and efficient supporting means for bracing the axle at its central portion.
- 15 Another object of this invention is the production of a truss which is provided with a plurality of clamping members which are so formed as to securely hold the truss rods in their correct position upon the rear axle.
- 20 With these and other objects this invention consists of certain novel combinations, constructions and arrangements of parts as will be hereinafter fully described and claimed.
- 25 In the accompanying drawing: Figure 1 is an elevation of the rear axle and other portions of an automobile showing the truss members attached thereto. Fig. 2 is a section taken on the line 2—2 of Fig. 1. Fig. 30 3 is a section taken on the line 3—3 of Fig. 1. Fig. 4 is a detailed perspective view of one of the clamps. Fig. 5 is a plan view of the complete truss showing the same detached.
- 25 Referring to the accompanying drawing by numerals 1 indicates the usual axle which is supported by the wheels 2 and which is provided at its central portion with the gear housing 3.
- 40 In order to prevent the axle 1 from breaking at the central portion or adjacent the housing 3 and for the purpose of supporting the axle in its correct position so as to allow the gear within the housing 3 to efficiently 45 operate there are provided a plurality of truss rods which extend upon the outer portion of the axle and which bear thereon to efficiently support the same. A truss rod 4 extends so as to brace the rear portion of the axle 1 by bearing upon the rear portion of the housing 3 while the truss rod 5 extends under the axle as clearly disclosed in Fig. 1 so as to support the same. It will be seen that the truss rods 4 and 5 are each 50 provided at their central portion with a
- 55 pocket 6 for the reception of the gear housing 3.
- For the purpose of supporting the truss rods 4 and 5 in their correct position there is provided adjacent each end of the axle 1 60 a clamp which is adapted to engage the end portions of the truss rods for holding these rods in their correct position upon the axle 1. Each clamp comprises a primary section 7 and an auxiliary section 8 which are 65 bowed so as to fit upon the axle 1. The auxiliary section 8 is provided with laterally extending feet 9 which are adapted to engage the laterally extending feet 10 of the primary section 7. Securing bolts 11 are 70 then passed through these feet 9 and 10 for securely holding the clamps in their correct position upon the axle. The primary section 7 is provided with the depending lug 12 upon its lower side which is provided 75 with a transverse opening 13 for the reception of the lower truss rod 5. This truss rod 5 is provided with a head 14 for preventing the rod from moving from engagement with the lug 12. Between this lug 12 80 and one of the feet 10 there is provided a diagonally extending lug 15 having a transverse opening 16 adapted to receive the truss rod 4, this truss rod being provided with the usual head 14'. Since these lugs 85 12 and 15 are formed upon the primary section 7 as above described they will be formed at a spaced distance apart so as to easily engage the truss rods 4 and 5 for holding the truss rods in their correct spaced relation upon the rear axle whereby the rear 90 axle will be efficiently supported.
- From the above description it will be seen that the sections may be easily taken apart when it is desired to remove the truss member from the rear axle or when it is desired to place the same thereon whereby any 95 changes which are desired to be made may be easily done without interference from the truss member.
- 100 What is claimed, is:—
- In a rear axle truss for automobiles, the combination with an axle, a plurality of truss rods, one of said rods adapted to fit upon the lower portion of the axle and the other rod adapted to fit upon the rear portion of the axle, a clamp carried by the axle adjacent each end thereof, each clamp comprising a primary and an auxiliary section, 105 said sections adapted to be secured together 110

for holding said clamp in position, each of said primary sections provided upon its lower side with a depending lug, each of said primary sections also provided with a 5 diagonally extending lug formed adjacent said depending lug, said lugs provided with transverse openings adapted to receive said truss rods whereby said truss rods will efficiently brace the central portion of the axle,

said lugs being formed in a position to efficiently hold said truss rods in their correct positions.

In testimony whereof I hereunto affix my signature in presence of two witnesses.

HERMAN H. SUNVOLD.
